UNITED STATES PATENT OFFICE.

LEBRECHT FRITZSCHE, OF NEWARK, NEW JERSEY.

DESIGN FOR A SUGAR OR CONFECTIONERY TONGS.

No. 39,445.

Specification for Design.

Patented Aug. 18, 1908.

Application filed October 29, 1904. Serial No. 230,616. Term of patent 3½ years.

To all whom it may concern:

Be it known that I, LEBRECHT FRITZSCHE, a citizen of the United States, residing at Newark, in the county of Essex and State of New Jersey, have invented a new, original, and ornamental Design for Sugar or Confectionery Tongs, of which the following is a specification, reference being had to the accompanying drawing, forming a part thereof.

The figure is a perspective view of a sugar or confectionery tongs showing my new design.

I claim:

The ornamental design for a sugar or confectionery tongs as shown.

LEBRECHT FRITZSCHE.
